UNITED STATES PATENT OFFICE.

ACHILLO FABRIZIO, OF ELKTON, MARYLAND.

TOY TORPEDO.

Application filed March 10, 1924. Serial No. 698,046.

To all whom it may concern:

Be it known that I, ACHILLO FABRIZIO, a subject of the King of Italy, residing at Elkton, in the county of Cecil and State of Maryland, have invented certain new and useful Improvements in Toy Torpedoes, of which the following is a specification.

My invention relates to toy torpedoes and methods of making the same.

10 It is a well recognized fact in the torpedo industry that a torpedo should have a casing of uniform strength. Casings of nearly uniform strength, have been devised, but their construction was so expensive as to 15 prohibit their manufacture.

The objects of my invention are to provide a torpedo of inexpensive construction which may be made of any desired size and strength and which will always be of practically uniform strength throughout its entire casing and to provide a novel method 20 for making the body of the casing.

These objects, and other advantageous ends which will be described hereinafter, I 25 attain in the following manner, reference being had to the accompanying drawing in which—

Figure 1 is a perspective view of a tube which is to be formed into the body of the 30 casing with a spheroidal bottom,

Figure 2 a perspective view of the tube shown in Figure 1 having in accordance with my novel method, and spheroidal bottom formed thereon,

35 Figure 3 a central section through a torpedo constructed in accordance with my invention and having a coating of adhesive material applied thereto.

Referring to the drawings, 1 indicates a 40 casing having a spheroidal bottom 2 and an open top 3. A cap 4 closes top 3 and is secured to casing 1 by adhesive material. Any suitable explosive material 5 is placed within the casing. If desired a reinforcing 45 band 6 is secured to cap 4 in casing 1 by adhesive material. A coating of adhesive 7 is applied to the casing to reinforce the same.

The methods of making my improved 50 torpedo consists of cutting cylindrical tubes

shown in Figure 1 and forming the spheroidal bottom 2 as shown in Figure 2. This spheroidal bottom may be formed in any suitable manner, preferably by softening the bottom of the tube and twisting the bottom 55 to take a spheroidal shape. The softening of the tube, if made of paper, may be done by dipping it in water and if of composition by dipping it into a solvent and then drying. The casing 1 is filled with the explosive material 5 and cap 4, which may be made in any suitable manner, is placed over casing 1 to cover the same. I preferably coat the inner side walls of the cap with adhesive material so that it will adhere to 60 the casing. If desired the cap may be secured to the casing solely by the reinforcing strip 6 which is glued to the casing and to the cap. If desired the torpedo is then dipped into a bath of adhesive material to 65 reinforce the same. The torpedo is then 70 dried and is ready for use.

A torpedo made in this manner may be of any desired length without affecting its uniformity in strength, because varying the 75 length of casing 1 does not effect its strength.

Having thus described my invention, what I claim as new and desire to secure by Letters Patent is:—

1. A torpedo including a tubular casing having its upper end open and its lower end formed into a spheroidal bottom; explosive material in the casing, and a tubular cap having a flat top secured to and closing the 80 upper end of the casing.

2. A torpedo including a cylindrical casing having its upper end open and its lower end formed into a spheroidal bottom; explosive material in the casing; and a cylindrical cap having a flat top secured to and closing the upper end of the casing.

3. A torpedo including a tubular casing having its upper end open and its lower end formed into a spheroidal bottom; explosive material in the casing; a tubular cap having a flat top secured to and closing the upper end of the casing, and a reinforcing band secured to the cap and the casing.

4. A torpedo including a tubular casing 100

having its upper end open and its lower end formed into a spheroidal bottom; explosive material in the casing; a tubular cap having a flat top secured to and closing the upper end of the casing, and a coating of adhesive material on the cap and the casing.

5 In testimony whereof I have signed my

name to this specification in the presence of two subscribing witnesses.

ACHILLO FABRIZIO.
